US0D1104770S

(12) United States Design Patent (10) Patent No.: US D1,104,770 S
(45) Date of Patent: * Dec. 9, 2025

(54) FRAGRANCE BOTTLE WITH CAP

(71) Applicant: Lash Music LLC, Beverly Hills, CA (US)

(72) Inventor: Jon Dinapoli, Long Branch, NJ (US)

(73) Assignee: Lash Music, LLC, Beverly Hills, CA (US)

() Term: 15 Years

(21) Appl. No.: 29/965,647

(22) Filed: Sep. 27, 2024

(51) LOC (15) Cl. 09-01

(52) U.S. Cl.

USPC D9/600; D9/682

(58) Field of Classification Search
